United States Patent Office

Des. 215,976

Patented Nov. 11, 1969

215,976

HORN OR SIMILAR ARTICLE

Charles Berns, Brookfield, Conn., assignor to Edwards Company, Inc., Norwalk, Conn., a corporation of Connecticut

Filed Nov. 14, 1968, Ser. No. 14,449

Term of patent 14 years

Int. Cl. D29—99

U.S. Cl. D72—1

FIG. 1

FIG. 4

FIG. 2

FIG. 5

FIG. 3

FIG. 1 is a top view of a horn or similar article according to my new design.

FIG. 2 is a front view of the horn or similar article.

FIG. 3 is a bottom view of the horn or similar article.

FIG. 4 is a side view of the horn or similar article.

FIG. 5 is a back view of the horn or similar article.

The medallion is shown in broken line in FIG. 2 for illustrative purposes only.

I claim:

The ornamental design for a horn or similar article, as shown and described.
